SPARK PLUG

Wilfred A. Bychinsky, Ann Arbor, and Alfred Candelise, Flint, Mich., assignors to General Motors Corporation, Detroit, Mich., a corporation of Delaware

Application January 19, 1954, Serial No. 404,878

2 Claims. (Cl. 313—144)

This invention relates to spark plugs, and more particularly, to spark plugs of the type having a metal shielded insulator and used primarily in aircraft engines. Such aircraft spark plugs have an insulator with an upper portion which is tubular in shape for the reception of an ignition cable. This tubular insulator portion is protected by a metal shielding barrel the lower end of which is secured to the spark plug shell. It has heretofore been the practice to secure the shielding barrel to the spark plug shell by brazing or soldering this being the sole means for holding the two parts together. There have been instances of such a joint failing during operation of the spark plug due to the shock, vibration and high temperatures encountered, thus resulting in the barrel coming loose from the spark plug shell. Such failures are particularly troublesome because they often occur while the aircraft is in flight and thus present a tremendous safety hazard. Not only is one cylinder of the aircraft engine thereby made inoperative, but also, because of the loose parts which result, serious damage may be caused to other parts of the engine.

It is an object of the present invention to provide an aircraft spark plug which is more durable and more reliable than those heretofore used.

More specifically, it is an object of the present invention to provide a shielded aircraft spark plug with improved means for securing the insulator shielding barrel to the spark plug shell and to provide an improved method for making same.

These objects are carried out in accordance with the invention by the provision of a mechanical lock in addition to the braze, between the shielding barrel and the spark plug shell. In the preferred embodiment this mechanical lock is accomplished by a cooperating flange and shoulder arrangement between the joined parts.

Other objects and advantages of the invention will appear more clearly from the following detailed description and from the drawing which shows a cross sectional view of the preferred embodiment.

Referring now to the drawing, there is shown an aircraft spark plug comprising an elongated insulator member 2 carrying a center electrode assembly 4 in the center bore thereof, a generally tubular metal shell 6 carrying ground electrode 8, and metal shielding barrel 10 which concentrically surrounds the upper end of the insulator and which is secured to the shell 6 in accordance with the present invention.

The insulator member is provided with a lower shoulder 12 and also with an upper shoulder 14 of slightly larger diameter. The upper end 16 of the insulator is tubularly shaped for the reception of an insulated ignition cable (not shown) having an electrical connector at its lower end to establish electrical contact with the spark plug central electrode assembly.

The central electrode assembly includes metal contact plug 18, resistor element 20, conductive glass seal 22 and firing tip 24 having an upper portion embedded in the glass seal 22 and a lower portion extending below

2

the lower end of the insulator in spaced relation to ground electrode 8 to form a spark gap therewith. A spiral spring 26 presses resistor element 20 against metal plug member 28 which is embedded in a glass seal 22, 5 thereby assuring electrical contact.

The metal shell 6 is provided with an internal ridge 30 which cooperates with the shoulder 12 to support the insulator. The upper portion 31 of the shell is of increased diameter to accommodate the insulator shoulder 14.

The lower end of the shielding barrel 10 is of smaller diameter than the upper end of shell 6 and is positioned concentrically therewithin, the tapered lower edge 32 of the barrel cooperating with shoulder 14 to maintain the insulator securely and properly positioned within the shell. Metal gaskets 34 and 36 assure a good seal and a firm seating of the insulator.

In accordance with the invention, the top edge of the shell is turned or bent inwardly so as to form an annular flange 38 which is pressed over and engages an external annular shoulder 40 formed in the shielding barrel. The top edge of the shell which forms flange 38 is preferably of slightly reduced thickness, in comparison with the rest of the shell, in order to facilitate the turning or bending operation. In the embodiment shown, the shoulder 40 is provided by forming an annular groove 41 on the barrel 10. This cooperating flange and shoulder arrangement forms a mechanical lock which assures against loosening of the parts. Additionally, the shield 10 is brazed to the shell as shown at 42. It is preferable to form the insulator 2 with a slightly reduced diameter adjacent the brazing zone, as shown at 46, in order to prevent insulator breakage due to heat shock during the brazing operation.

In manufacturing the spark plug, the insulator 2, with center electrode assembly 4 already secured within the centerbore, is first positioned in shell 6. A ring of silver solder or other suitable brazing material is placed in groove 44 which is formed in the lower end of the barrel 10. Then the barrel is seated concentrically within the shell and heat is applied in the vicinity of the ring of brazing material. Capillary action causes the fused brazing material to run out of the groove 44 and between the shell and barrel to form the joint as shown at 42. 45 It is preferable to coat the surfaces on the barrel and shell to be brazed with a suitable flux in order to assist the spreading of the brazing material between the parts.

After the brazing operation is completed, the upper edge of the shell is turned inwardly and over the shoulder 40 to form flange 38. With the parts thus secured, 50 a high amperage current is passed through the shell to heat and thereby soften the thin section 48 and pressure is simultaneously applied to the ends of the shell. This latter operation collapses thin section 48 thereby wedging insulator shoulders 12 and 14 between the lower edge 32 of the barrel and ridge 36 respectively to tightly secure the insulator within the shell.

It will be obvious that if the distance between insulator shoulders 12 and 14 is too great, or too small, 60 the flange 38 will not properly engage the shoulder 40. Thus where there is to be high production of the spark plug of this invention, it is important that the insulator members used be of relatively uniform size. If the insulator lengths vary considerably it may be necessary 65 to machine to proper size the top edge of each spark plug shell just prior to turning it inwardly to form the flange 38.

Aircraft spark plugs made in accordance with the present invention are more durable and more reliable than 70 those heretofore used. The mechanical interlock provided between the shielding barrel and the shell by means of the flange and shoulder structure assures against loos-

ening of the parts even under the most adverse operating conditions wherein high temperatures, vibration and mechanical shock are encountered.

It is to be understood that, although the invention has been described with specific reference to a particular embodiment thereof, it is not to be so limited since changes and alterations therein may be made which are within the full intended scope of this invention as defined by the appended claims.

What is claimed is:

1. A spark plug comprising a tubular metal shell carrying a ground electrode at the lower end thereof, said shell having a lower portion of smaller diameter than the top portion thereof and being provided with an internal annular ridge, a metal barrel having a lower portion positioned concentrically within the top portion of said shell and brazed thereto, the upper end of said shell having an annular flange turned inwardly and over a shoulder formed on said barrel to lock said shell and said barrel together, an elongated insulator within said shell having a tubular shaped upper portion positioned concentrically within said barrel, said insulator having a lower shoulder engaging said ridge and an upper shoulder positioned in the top portion of said shell and engaging the lower end of said barrel, and a center electrode extending from the lower end of said insulator in spaced relation to said ground electrode to form a spark gap therewith.

2. A spark plug comprising a tubular metal shell carrying a ground electrode at the lower end thereof, said shell having a lower portion of smaller diameter

than the top portion thereof and being provided with an internal annular ridge, a metal barrel having a lower portion positioned concentrically within the top portion of said shell and brazed thereto, the upper end of said shell having an annular flange turned inwardly and over a shoulder formed on said barrel locking said shell and said barrel together, an elongated insulator within said shell having a tubular shaped upper portion positioned concentrically within said barrel, said insulator having a lower shoulder engaging said ridge, an upper shoulder positioned in the top portion of said shell and engaging the lower end of said barrel and a portion of reduced diameter adjacent the lower portion of said barrel providing an annular space between said insulator and said barrel, and a center electrode extending from the lower end of said insulator in spaced relation to said ground electrode to form a spark gap therewith.
